UNITED STATES PATENT OFFICE.

WILLIAM HAMER, JR., OF BURY, ENGLAND.

STEAM GENERATOR.

Application filed December 31, 1919. Serial No. 348,657.

To all whom it may concern:

Be it known that I, WILLIAM HAMER, Junior, a subject of the King of Great Britain and Ireland, and a resident of Bury, in the county of Lancaster, England, have invented certain new and useful Improvements Connected with Steam Generators, of which the following is a specification.

This invention relates to steam generators of the Lancashire, Cornish and like types set in masonry and having external flues.

The front wall of the setting of boilers of the types referred to is set back or recessed below the boiler to form a chamber to clear and enclose the blow-off or mud cock of the boiler. Owing to the more or less continual presence of moisture in said chamber and on the walls thereof coupled with the movements of the boiler shell under expansion and contraction, the joint between the walls of the chamber and the boiler is liable to be impaired allowing leakage of the flue gases and/or cold air to be drawn into the flues from outside. The object of the present invention is to provide means for maintaining a tight joint between said wall or walls and the boiler shell and so preventing leakage of the flue gases and/or cold air passing from the outside into the flues.

According to the invention, I provide a yieldable joint-member or members shaped to fit against the boiler shell and mounted to make a tight joint between same and the walls of the blow-off or mud cock chamber. In conjunction with said yieldable joint member or members I may employ asbestos rope or other appropriate incombustible packing.

In the accompanying drawing, Fig. 1 is a transverse section of a generator of the kind referred to embodying one form of yielding joint between the walls of the blow-off or mud cock chamber and the boiler shell the section being taken approximately along the line 1—1 of Fig. 2, Fig. 2 is a plan with the boiler removed, showing the joint-member and its guide arranged in position on the top of the walls of the chamber, Fig. 3 is a part longitudinal section of the chamber, the section being taken approximately along the line 3—3 of Fig. 1, but with the boiler in elevation, and Fig. 4 is a perspective view of the joint-member and its guide separated. Fig. 5 is an enlarged section of the joint-member and guide illustrating means which I may employ for facilitating

the fitment thereof. Fig. 6 is a part sectional view illustrating the arrangement of spiral springs for pressing the joint-member against the boiler shell, and Fig. 7 is a similar view illustrating a modified arrangement of springs.

Referring to the drawing, *a* is the boiler, *b* the blow-off or mud cock at the front end thereof, and *c* the chamber formed in the front wall *d* of the setting to clear and enclose the cock *b*.

According to the illustrated way of carrying the invention into practice, the walls of the chamber *c* are stopped short of the underside of the boiler shell and between the latter and the top of the walls I arrange a joint-member *e* and a guide *f* wherein the joint-member is mounted and adapted to slide or yield vertically. The joint-member *e* and guide *f* are of approximately U shape in plan to conform to the shape of the chamber *c*. The sides of the joint-member and guide are straight and their ends are curved parallel to the radius of the boiler shell. As shown best in Fig. 5, the guide *f* is of double channel of more or less H section and the joint-member *e* is formed with a tail portion *e*¹ adapted to enter and slide in the upper channel *f*¹ of the guide, springs *g* being provided between the tail portion *e*¹ and the web *f*² of the guide to press the joint member upwards and against the boiler shell. Preferably, and as shown best in Figs. 5 and 6, I employ a plurality of spiral springs *g* mounted on set-screws *h* which pass freely through the web *f*² and are screwed into the tail portion *e*¹. I may, however, employ undulating blade springs *g*¹ for pressing the joint-member against the boiler shell, as shown in Fig. 7, or any other appropriate arrangement of springs.

Asbestos rope or other appropriate packing *j* is preferably provided between the joint-member *e* and the boiler shell, the jointing face of the member being conveniently arched or grooved to receive and position the packing. The channels *f*¹, *f*³ of the guide *f* may be packed with slag wool or other suitable packing *k* to prevent the flue gases escaping or cold air passing through the guide.

For facilitating the fitting of the device, I may provide at suitable points, holes in the tail portion *e*¹ of the joint-member *e* and the guide *f* for the insertion of cotters or the like *m*, Fig. 5, to hold the joint mem-

ber retracted while the device is being fitted in position when the cotters or the like are withdrawn.

It will be seen that the joint-member *e* being pressed by the springs is free to yield to and follow movements of the boiler shell and any settlement or disturbance of the walls of the chamber *c*.

As will be obvious, instead of the joint-member being made in a single piece, it may be made in sections, e. g., two side pieces and an end piece.

What I claim as my invention, and desire to secure by Letters Patent is:—

15 1. In a steam generator, having a shell and a supporting wall with a reentrant portion for clearing a boiler blow off cock, a guide extending along the reentrant portion of the wall, a closure member extending 20 along the guide and carried thereby for movement toward and from the shell to close the space between the guide and shell, means for yieldingly pressing the closure member toward the shell, and deformable 25 packing means carried by the closure member for actual engagement with the boiler shell.

2. In a steam generator having a shell and a supporting wall with a reentrant portion in the end thereof for clearing a boiler 30

blow-off cock, a guide extending along the upper face of the reentrant portion and having a channel in its upper face, a closure member extending into the channel and slideable therein toward and from the shell to close the space between the guide and shell, means for yieldingly pressing the closure member toward the shell, and deformable packing means carried by the closure member for actual engagement with the boiler 40 shell.

3. In a steam generator having a shell and a supporting wall with a reentrant portion in the end thereof for clearing a boiler blow-off cock, a guide extending along the upper face of the reentrant portion and having a channel in its upper face, a closure member extending into the channel and slideable therein toward and from the shell to close the space between the guide and shell, means for yieldingly pressing the closure member toward the shell, deformable packing means carried by the closure member for actual engagement with the boiler 45 shell and additional packing means for preventing leakage of air or gases through 50 the channel and around the closure member.

In witness whereof I have hereunto set my hand.

WILLIAM HAMER (JUNIOR).
